UNITED STATES PATENT OFFICE.

FRITZ DAHLIN, OF WEST MOSHANNON, PENNSYLVANIA.

CAN OPENER.

Application filed May 22, 1922. Serial No. 562,897.

To all whom it may concern:

Be it known that I, FRITZ DAHLIN, a citizen of the United States, residing at West Moshannon, in the county of Clearfield and 5 State of Pennsylvania, have invented new and useful Improvements in Can Openers, of which the following is a specification.

This invention aims to provide a can opener which can be operated with the expenditure of a minimum amount of effort 10 and designed to eliminate all possibility of the user from being injured incident to the slipping of the knife blade from the can as frequently occurs with other openers with 15 which I am familiar.

Another object of the invention resides in the provision of a device of the above mentioned character designed to rigidly support the can while the latter is being opened, 20 and including means for this purpose which is susceptible of adjustment to accommodate itself to cans of different size.

A further object of the invention resides in the provision of a can opener including 25 a can supporting frame and a rotatable cutter blade, the latter being capable of adjustment so as to be properly positioned with respect to cans of different size.

The nature and advantages of the invention 30 will be better understood when the following detailed description is read in connection with the accompanying drawings, the invention residing in the construction, combination, and arrangement of parts as 35 claimed.

In the drawings forming part of this application, like numerals of reference indicate similar parts in the several views, and wherein:—

40 Figure 1 is a view in elevation showing the invention supporting a can for the purpose specified.

Figure 2 is a sectional view taken on line 2—2 of Figure 1.

45 Figure 3 is a sectional view taken on the line 3—3 of Figure 1.

Figure 4 is an enlarged fragmentary sectional view of the cutting blade and its supporting means.

50 Figure 5 is a sectional view taken on line 5—5 of Figure 3.

Referring to the drawings in detail, 10 indicates a base from which rises a plurality of standards 11, the latter being suitably connected together by spaced annuli 12, these parts unitedly defining a frame-like

structure which is adapted to receive and support the can 13 while the top of the latter is being severed. Supported by the standards 11 are suitable bearings 14 for pinions 15, the latter being threadedly associated with the clamping elements 16, there being one of these elements for each pinion. The clamping elements are horizontally disposed, and the corresponding inner extremities of 60 said elements support arcuate-shaped members 17 to accommodate themselves to the curvature of the can 13. The clamping elements 16 are susceptible of movement toward and away from each other, or in other 65 words moved radially to engage cans of different diameters, and for the purpose of simultaneously adjusting said clamping elements, I provide a ring gear 18, the teeth of which mesh with the pinions 15. A crank 70 handle 19 is journaled upon one of the standards 11 and supports a pinion 20 associated with the ring gear to turn the latter incident to the rotation of the said handle. Manifestly, when the handle is turned in 75 one direction, the clamping elements 16 are moved inwardly in unison to effectively engage the can supported upon the base 10, and when rotated in an opposite direction, causes 80 the clamping elements to move outwardly or 85 away from the can to release the latter.

The frame-like structure above described, includes a cover 21 which is hinged as at 90 22 upon one of the standards 11, and the cover carries suitable fastening elements 23 to hold the cover in its closed position. Rotatably mounted upon the underside of the cover 21 is a ring gear 24 which is rotated through the instrumentality of a pinion 25, the latter being carried by a handle 26, associated with the cover for rotating the pinion. Arranged transversely of the ring gear is a cross piece 27 which is grooved as at 28 to slidably receive a block 29, the block having a threaded bore 30 which receives a threaded adjusting element 31, one end of which is provided with a knob or the like 32. Carried by the opposite end of this adjustable element is a cutter blade 33 which is associated with the element by means of 95 suitable fastening elements 34 in a manner to permit the cutting blade to be removed therefrom when the occasion requires. The cutting blade may be of any suitable size or configuration without departing from the spirit of the invention. By reason of this construction, it is manifest that the adjust- 100 105 110

ing element with which the blade is associated, can be adjusted vertically to position the blade with respect to the top of the can to be severed, in order that the cutting blade may properly penetrate the can, and that the block 28 slidable in the cross piece 27 allows the cutting blade to be moved across the top of the can to be positioned adjacent one edge thereof, irrespective of the size or diameter of the can.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

20 A can opener comprising a frame like structure, a hinged cover for said frame like structure, a ring gear supported by the cover

for rotation, a crank handle journalled on said supporting structure, a pinion carried by said handle and meshing with the gear 25 to rotate the latter, a cross bar arranged centrally of said gear and carried thereby and having a longitudinal slot, the opposed sides of said slot being of channel like formation in cross section, a block arranged in said channel like portion for movement longitudinally of the cross bar, a threaded element passing through said block and arranged vertically on said cover and adapted to be adjusted toward and away from the can, and a cutting blade carried by the lower end of said adjusting element and adapted to be forced through the top of the can and removing the latter as said gear is rotated.

35 In testimony whereof I affix my signature.

40 FRITZ DAHLIN.
